**COMBINED PROPANE TORCH AND
IGNITER ASSEMBLY**

William L. Lindgren, Sycamore, Ill., assignor to Turner Corporation, Sycamore, Ill., a corporation of Illinois
Filed Dec. 18, 1963, Ser. No. 331,402
4 Claims. (Cl. 158—33)

This invention relates to improvements in portable torches of the propane gas type and more particularly relates to an improved form of combined torch and igniter assembly.

A principal object of the present invention is to provide an improved form of torch assembly having an igniter as a part thereof and arranged with a view toward utmost simplicity in construction and safety in operation.

A further object of the invention is to provide a propane torch and igniter assembly of a novel and simplified construction, in which the igniter is a part of the torch and is positionable over the nozzle of the torch during the igniting operation and effects ignition of the gas issuing from the torch burner nozzle with the utmost safety to the user.

A further object of the invention is to provide a simple and improved form of igniter for propane torches and the like, so constructed and arranged as to be a part of the torch assembly, and positionable to effectively ignite a gas issuing from the burner nozzle and to direct the flame of the ignited gas away from the hand of the user of the torch.

Still another object of the invention is to provide an improved form of igniter for propane torch and the like in which a spark igniter is a part of the torch assembly and is manually positionable in a most effective and safe position for igniting the torch.

These and other objects of the invention will appear from time to time as the following specification proceeds and with reference to the accompanying drawing wherein:

FIGURE 1 is a view in side elevation of a torch and igniter constructed in accordance with the principles of the present invention with certain parts broken away and certain other parts shown in section; and

FIGURE 2 is a plan view of the igniter shown in FIGURE 1.

In the embodiment of the invention illustrated in FIGURE 1 of the drawings, I have shown a torch and igniter assembly 10, adapted to be assembled on a propane tank 11 of a size that may readily be grasped by the hand, and forming a source of supply of fuel for the torch. The torch and igniter assembly 10 generally includes a valve body 12 having an enlarged diameter internally threaded integral fitting 13 at one end for threading on the end of the propane bottle or tank 11 and having a knob 15 to one side thereof, for operating a valve (not shown) to vary the supply of fuel to a burner assembly 16. The valve body 12 has an orifice or fuel passage 17 having communication with a fitting 18 threaded therein and threaded or otherwise secured to one end of a tube 19 having the burner assembly 16 threaded on its outer end. The tube 19 supplies fuel, such as propane, to the usual orifice block 20 supplying a metered volume of fuel to the burner nozzle (not shown). The burner assembly is encircled by a cylindrical sleeve 21, forming a windshield to shield the burner flame from wind.

The tube 19 has a bifurcated bracket 22 extending therefrom at right angles with respect thereto adjacent the burner assembly and generally on the underside of the tube 19, when the torch is in the upright position shown in FIGURE 1. The bracket 22 forms a pivotal position shown in FIGURE 1. The bracket 22 forms

2

a pivotal mounting for an igniter 23 on a pivot pin 24.

The igniter 23 is in the general form of a tube 25, the wall of which is cut away at the rear end portion of said tube, forming spaced connector ears 26 extending between the furcations of the bifurcated bracket 22 and pivotally connected to said bracket as by the pivot pin 24. A torsion spring 27 is shown as having one end hooked to the bracket 23 and as being turned about the pivot pin 24 and having an opposite end engaging the inner wall of the tube 25 and biasing the tube towards the valve body 12 into the inoperative position as shown in FIGURE 1.

The tube 25 also has an outturned outer end portion recessed inwardly of the tube as indicated by reference character 28 to form a widened hood 29 spaced from the end of the windshield 21 and extending over the end of said windshield when the igniter is in its operative igniting position. The hood 29 thus deflects the gas issuing from the nozzle assembly 16 to pass along said tube to a flint 30 and spark wheel 31. The flint 30 may be guided within a housing 32 extending along the central portion of the tube 25 and having communication with the interior of said tube through a slot 33 in the wall of said tube and extending beyond opposite ends of said housing. The flint 30 may be the usual pyrophoric element comprising a material such as ferrocium and is resiliently biased against the spark wheel 31 by a releasable plunger 35 extending along the housing 32 and slot 33 and guided in a rear wall 37 of said housing. A spring 36 encircles the plunger 35 and is seated at one end in the rear wall 37 of the housing 32, and at its opposite end on an upright end 39 of the plunger 35. The upright end 39 in turn has biasing engagement with the flint 30 to maintain the flint in contact with the spark wheel 31. The spark wheel 31 is mounted in an enlarged forward end portion 40 of the slot 33, adjacent the hood 29, on a pivot pin 41. The pivot pin 41 may be in the form of a rivet mounted at its ends in spaced brackets 42 extending along opposite sides of the spark wheel 31 upwardly of the opposite margins of the enlarged forward end portion 40 of the slot 33. The pivot pin 41 and brackets 42 thus position the spark wheel 40 to extend within the tube closely adjacent the opening of said tube into the hood 29 into engagement with the flint 30. The spark wheel 40 may be of a conventional form having a roughened or serrated periphery engaging the flint 22, and creating a spark when turned by hand.

When it is desired to ignite the torch and the valve 15 is turned to an "on" position, assuming the igniter has been moved to the broken line position shown in FIGURE 1, it is merely necessary to turn the spark wheel 31 by the thumb, or one of the fingers of the hand in a counterclockwise direction to create a spark and ignite the gas issuing from the nozzle assembly 16, it being understood that the hood 29 extending over the end of the windshield 21 deflects the gas into the region of the flint and spark wheel and that the tube itself serves to draw the gas therethrough, to be ignited upon turning of the spark wheel.

It may thus be seen that the spark wheel and flint are placed closely adjacent the outer end of the windshield 21 and that the hood collects and deflects sufficient gas into the tube to be readily ignited without danger to the operator of the torch and igniter. It may further be evident that once the gas issuing from the nozzle assembly is ignited, the hood will tend to deflect the flame away from the hand of the operator until the hand is removed from the igniter assembly, at which time the torsion spring 27 will withdraw the igniter assembly to its inoperative position shown in FIGURE 1.

While I have herein shown and described one form in which the invention may be embodied, it may readily be understood that various variations and modifications in the invention may be attained without departing from the spirit and scope of the novel concepts thereof.

I claim as my invention:

1. In a spark igniter and in combination with a torch having a burner tube having a burner assembly extending from the end thereof and having communication with a source of supply of gas, means for igniting the gas issuing from said burner assembly comprising an igniter tube movably mounted on said burner tube for movement toward and from the open end of said burner assembly and normally biased into a position remote from said burner assembly, said igniter tube having a hooded end portion extending to one side thereof over the end of said nozzle assembly and spaced therefrom and having communication with the interior of said igniter tube, and flame initiating means mounted on said igniter tube closely adjacent said hood and including a spark wheel rotatably mounted on said igniter tube adjacent said hood and extending into said igniter tube, and a flint extending along said tube and biased into engagement with said spark wheel to create a spark in the region of said hood.

2. A torch and igniter assembly adapted for mounting on a propane type tank of a size that may readily be grasped by the hand and forming a source of fuel for the torch, a bracket extending from the torch, an igniter tube pivotally mounted at one end on said bracket for movement from an inoperative position to an operative igniting position, spring means biasing said igniter tube into an inoperative position, said igniter tube having a recessed free end portion having a hood extending thereover and having a concave gas deflecting surface forming a continuation of the interior of said tube, said tube also having a slot extending therewith from a position closely adjacent said recessed portion and hood, to the end thereof pivoted to said bracket, an igniter wheel mounted in said slot adjacent said hood, for rotatable movement into the hollow interior portion of said tube, a flint mounted in said slot and biased into engagement with said igniter wheel for creating a gas igniting spark upon the turning of said spark wheel by the hand.

3. A torch and igniter assembly adapted for mounting on a propane tank of a size that may readily be grasped by the hand and form a source of fuel for the torch, a bracket extending from the torch, an igniter tube open at each end, pivotally mounted on said bracket for movement from an inoperative position to an operative igniting position, spring means biasing said igniter tube into an inoperative position, said igniter tube having a recessed free end portion having a hood extending thereover from one side thereof, said hood having a concave deflection surface extending from a position to one side of said tube within said tube and generally forming a forward continuation of said tube, said tube also having a slot extending along the wall thereof on the side

thereof opposite the torch, when said tube is in an operative igniting position, spaced brackets extending upwardly of opposite sides of said slot adjacent said tube, an igniter wheel rotatably mounted on said brackets for movement into the interior of said tube, a housing extending rearwardly of said igniter wheel along said slot for a portion of the length thereof, a plunger movable along said slot and housing, a spring encircling said plunger and biasing said plunger toward said igniter wheel, and a flint slidably mounted in said housing and biased by said plunger and spring into engagement with said igniter wheel.

4. A torch and igniter assembly adapted for mounting on a propane tank of a size that may readily be grasped by the hand and form a source of fuel for the torch, a bracket extending from the torch, an igniter tube open at each end, pivotally mounted on said bracket for movement from an inoperative position to an operative igniting position at the end of the burner assembly for the torch, spring means biasing said igniter tube into an inoperative position, said igniter tube having a recessed free end portion having a hood extending thereover from one side of said tube, said hood having a concave deflection surface extending from a position to one side of said tube within said tube and forming a generally forward and lateral continuation of said tube extending over the burner assembly, said tube also having a slot extending along the wall thereof along the side thereof opposite the torch, when said tube is in an operative igniting position, spaced brackets extending upwardly of opposite sides of said slot adjacent said tube, an igniter wheel rotatably mounted on said brackets for movement into the interior of said tube, a housing extending along said slot rearwardly of said igniter tube and terminating forwardly of the rear end of said slot, said housing having a rear wall extending into said tube and across said slot, a plunger slidably guided in said rear wall and extending along said slot and having an upturned forward end portion engaging said flint, a spring encircling said plunger and interposed between said rear wall of said housing and said upturned end portion, said plunger also having an upturned rear end portion extending through said slot and outwardly of said tube affording a means for gripping said plunger by the finger and the like to release tension on said flint.
